UNITED STATES PATENT OFFICE.

JAMES A. SMITH, OF WINDSOR, CONNECTICUT.

THREADING DIE.

Application filed August 11, 1923. Serial No. 656,766.

My invention relates to the class of devices that are employed for cutting screw threads, and an object of my invention among others, is the production in a rapid, simple, and inexpensive manner of a die having improved features as to its characteristics.

My improved die and the manner of creating it, and in the construction and use of which the objects herein set out, as well as others, may be attained, is illustrated in the accompanying drawings, in which—

Figure 1 is a face view of a piece of material to form a die and upon which preliminary steps in the making of my improved die have been taken.

Figure 2 is a view in cross section through the same.

Figure 3 is a view similar to Figure 1, but illustrating an advanced step in the operation.

Figure 4 is a view in cross section through the same.

Figure 5 is an other view similar to Figure 1, but illustrating a still further and advanced step in the making of the die.

Figure 6 is a view in cross section through the same.

Figure 7 is a side view of a tool devised by me for use in carrying out my invention, this view also illustrating the manner of use of the tool.

Figure 8 is an end view of said tool.

Figure 9 is a face view of my improved die in its completed form.

Figure 10 is a view in cross section through the same.

Figure 11 is a view in cross section, scale enlarged, through my improved die on a plane denoted by the dotted line 11—11 of Figure 9, the scale being enlarged to clearly illustrate the improved characteristics of the die.

In the making of dies for cutting screw threads it has been common practice in the past to first drill a hole in the center of a piece of material to constitute a die, which hole is then tapped. Then a number of chip or clearance holes are made in the piece, these being located at equal distances apart and at such distances from the center and thread cutting hole as to enable the material between the center hole and the chip or clearance holes to be eventually cut away.

In order to cause the cutting threads of the center and threaded hole to readily cut

into and take hold of the piece upon which a thread is to be cut, and thus to begin the thread cutting operation upon such piece and to lead it into the die, the throat of the center and thread cutting hole is provided with what may be aptly termed a "lead" that takes the form of a bevel that extends in the direction of depth of the hole on the cutting portions or "lands", which are those parts located between the chip or clearance holes and extending towards the center of the die, and these beveled parts are also tapered backwardly from the front to the rear edges of such "lands", said front edges being those portions which travel ahead when the tool is operating to cut a thread.

In forming this "lead" it has been customary heretofore to employ a file, and in some instances a milling tool has been used, but either operation takes much time and requires great care and considerable skill to avoid mutilation of threads other than those upon which the work is being done. Consequently the formation of such lead has been an expensive operation, and, therefore, the original expense of the die has been considerable.

By employing my improved construction in the formation of a die I am enabled to produce such die in a particularly rapid and efficient manner and without requiring any special amount of skill, thus materially reducing the cost of producing the die, and at the same time I am enabled to provide a die that is more durable than those having the lead produced by a cutting operation as hereinbefore referred to. In constructing my improved die I first take a piece of material 10, of the desired form, as round or rectangular in cross section, and drill a center or thread cutting hole 11 therein, which hole is eventually beveled at its mouth or muzzle to produce the "lead," as hereinbefore described with respect to prior dies, the form or shape of this lead being substantially the same as that of prior dies.

The manner of forming this lead and the die having such lead is, however, an important feature of my present invention, which contemplates the formation of such lead by compressing or condensing the metal at the mouth of the thread cutting hole 11 and consequently at the entering ends of the "lands" 13, which compressing or condensing of the metal may be effected in any desired man-

ner, preferably by swaging. In the preferred manner of effecting this compressing or swaging operation, I employ a swaging or lead forming tool 12, properly shaped, and which is forced into the mouth of the hole to mold or swage the material of the "lands" about the mouth of the hole to the desired shape to produce the "lead." This operation of forming the lead may take place at different stages in making the die, but I prefer to form such lead as one of the preliminary steps in the operation. It will be found, however, that such lead may be formed after the center and thread cutting hole has been threaded, but by forming it before such threading, distortion of the threads is avoided and a subsequent operation to correct the distorted thread is not required.

In forming the "lead" of the die as herein contemplated I preferably construct said tool 12 with its working end properly shaped to produce the lead. This end of the tool is beveled to a degree to produce a beveled edge 14 of proper shape at the mouth of the thread cutting hole 11 and on the lands 13 should they exist at this time, and in order to properly shape the end of each land as to taper I provide as many swaging faces 15 on the tapered end of the tool as there are lands in the die to be made. These faces are tapered from a ridge 16 at one edge of each face to the bottom of a groove 17 that terminates at the perpendicular edge of the adjacent face, and as shown in Figure 7 of the drawings. In other words, each of the faces 15 of the tool is of a shape to correspond both in bevel and taper to the ends of the lands in the mouth of the hole in the die to be made, and when the tool is forced into the hole 11 those portions of the piece that will eventually comprise the ends of the lands 13, if the swaging be done in a preliminary step in the operation, or those portions constituting the ends of such lands, if the swaging be done after the formation of the threads, will be properly formed both as to taper and bevel to produce a most efficient lead.

When the swaging takes place as a preliminary step in the operation I preferably first form the center hole 11 and then the chip or clearance holes 18 are made. The tool 12 is then employed to produce the lead, as shown in Figures 3 and 4 of the drawing, the thread 19 may then be produced, as illustrated in Figures 5 and 6 of the drawing, and the entrances 20 to the chip holes 18 may then be cut in any desired manner to produce the completed die as illustrated in Figure 9.

When the lead is produced as a more advanced step in the operation, the work of the swaging tool is effected after the formation of the threads, and preferably after the chip or clearance holes 18 are made. It will,

therefore, be obvious that this swaging operation may take place at various stages in the construction of the die and I do not, therefore, limit my invention to the swaging as taking place at any special step in such construction.

A die produced as hereinbefore described has the metal of a working portion, that is the lead on the ends of the lands 13, compressed and condensed, with a consequent beneficial result of a cutting edge having increased durability over a die in which the metal is not condensed.

The bevels forming the leads on dies of various sizes are substantially the same, and it will, therefore, be obvious that a single swaging tool may be employed to bevel dies of a wide variety of sizes. A die produced in accordance with my invention will possess a maximum degree of uniformity as to the several cutting portions thereof, such uniformity greatly exceeding that possessed by a die in which the several cutting operations are separately performed by hand work.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim:—

1. A threading die having a thread cutting hole comprising a lead, with the metal comprised in such lead more dense than the metal comprised in parts of the thread cutting hole, thereby toughening a cutting part of the die.

2. A threading die having a thread cutting hole with a beveled mouth forming a lead, with the metal comprised in such lead more dense than the metal comprised in other parts of the hole, thereby toughening the cutting edge of the thread cutting hole in the die.

3. The process of forming a threading die that consists in making a thread cutting hole in a piece of material, and as a step in the process forcing the beveled end of a lead forming tool having backwardly tapered faces into the mouth of the thread cutting hole to compress the metal and form a lead.

4. The process of forming a threading die that consists in making a thread cutting hole in a piece of material, and as a step in the process compressing the metal at the mouth of said hole to form a lead, and afterwards threading said hole.

5. The process of forming a threading die that consists in making a thread cutting hole

in a piece of material, beveling the edge of said hole to form a lead, cutting chip or clearance holes before the beveling operation which holes are opened into the thread-cutting hole, and afterwards threading said thread cutting hole.

6. The process of forming a threading die that consists in making a thread cutting hole in a piece of material, forming clearance holes in said material with land portions therebetween, and as a step in the process forcing the beveled end of a lead forming tool having swaging faces larger in diameter than said thread cutting hole 10 into the mouth of said thread cutting hole and against the lands to compress the metal thereof to form a lead, and also, as a step 15

in the process, threading said thread cutting hole.

7. The process of forming a threading die 20 that consists in making a thread cutting hole in a piece of material, forming clearance holes in said material with land portions therebetween, and as a step in the process forcing the backwardly tapered annularly disposed swaging faces on the beveled end of a lead forming tool, said faces corresponding in number and location to said lands, into the mouth of said thread-cutting hole 25 and against said lands to compress the metal thereof to form the lead, and also, as a step 30 in the process, threading said thread-cutting hole.

JAMES A. SMITH.
